(57) **CLAIM**

The ornamental design for an ionizer, as shown and described.

DESCRIPTION

FIG. 1 is a front, top, and left side perspective view of an ionizer showing the new design;

FIG. 2 is a rear, bottom, and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is an enlarged view of the portion labeled 9 in FIG. 3;

FIG. 10 is an enlarged view of the portion labeled 10 in FIG. 4;

FIG. 11 is an enlarged view of the portion labeled 11 in FIG. 5;

FIG. 12 is an enlarged view of the portion labeled 12 in FIG. 6;

FIG. 13 is an enlarged view of the portion labeled 13 in FIG. 7;

FIG. 14 is an enlarged view of the portion labeled 14 in FIG. 8;

FIG. 15 is an enlarged view of the portion labeled 15 in FIG. 1; and,

FIG. 16 is an enlarged view of the portion labeled 16 in FIG. 2.

The broken lines shown in the figures are for the purpose of illustrating portions of the ionizer that form no part of the claimed design.

1 Claim, 12 Drawing Sheets
